UNITED STATES PATENT OFFICE.

OTTO F. FOGELSTRAND, OF KENSINGTON, CONNECTICUT, ASSIGNOR TO HART
MANUFACTURING COMPANY, OF SAME PLACE.

DESIGN FOR A COAT AND HAT HOOK.

Specification forming part of Design No. 5,499, dated January 30, 1872.

To all whom it may concern:

Be it known that I, OTTO F. FOGELSTRAND, of Kensington, in the county of Hartford and State of Connecticut, have invented and produced a new and original Design for a Coat and Hat Hook, of which the following is a specification:

The nature of my design is fully represented in the accompanying engraving, to which reference is made.

A represents the base of the hook, which base is bordered by a ledge, *a*, the space inclosed by said ledge being ornamented by means of transverse elevations and depres-

sions, as shown. The contour of the body of the hook *B* is composed of straight lines with angular corners. The ends *b b* of the hook *B* are formed by curved lines. The sides of the hook *B* have raised borders *c* and raised ornamental work, as shown.

I claim as my invention—

1. The design for the base *A* of a hook, as shown.
2. The design for the hook *B*, as shown.

OTTO F. FOGELSTRAND.
